UNITED STATES PATENT OFFICE.

WILLIAM S. LANEY, OF LITHOPOLIS, OHIO, ASSIGNOR OF ONE-HALF TO
NELLIE SCHILLER, OF KANSAS CITY, MISSOURI.

MECHANICAL MOTOR.

SPECIFICATION forming part of Letters Patent No. 625,691, dated May 23, 1899.

Application filed April 27, 1898. Serial No. 679,015. (No model.)

To all whom it may concern:

Be it known that I, WILLIAM S. LANEY, a citizen of the United States, residing at Lithopolis, in the county of Fairfield and State of Ohio, have invented certain new and useful Improvements in Mechanical Motors; and I do hereby declare the following to be a full, clear, and exact description of the invention, such as will enable others skilled in the art to 10 which it appertains to make and use the same.

This invention relates to mechanism for operating several devices simultaneously or individually; and it consists, essentially, of a supporting base and frame with drive-gear 15 ing thereon connected to the dasher-rod of a churn and also to an oscillating lever which has the plunger-rod of a washing-machine attached thereto, together with a grindstone revolved by a belt running from the same gear- 20 ing.

The invention further consists of the details of construction and arrangement of the several parts, which will be more fully herein- 25 after described and claimed.

The object of the invention is to provide 30 means for operating several devices from one point and utilize driving mechanism confined to one part of the device for several purposes, the several mechanisms being so positioned as to receive the applied power equally or proportionately in accordance with the work to be done.

In the accompanying drawings, Figure 1 is 35 a side elevation of a machine embodying the invention. Fig. 2 is an end elevation of the same. Fig. 3 is a detail elevation of part of the washing-machine. Fig. 4 is a section of the device shown by Fig. 3.

Referring to the drawings, wherein similar 40 numerals of reference are employed to indicate corresponding parts in the several views, the numeral 1 designates a base of any size or material, from which rise standards 2, preferably inclined inwardly, as shown by Fig. 2, 45 and having connected to their upper ends longitudinal side bars 3, which are connected by cross-ties 4. Depending from the upper portion of the superstructure and adjacent one end of the same is a hanger 5, in which a 50 drive-shaft 6 has bearing and extends outwardly through a suitable boxing attached to

one of the bars or beams 3. On the inner end of the said drive-shaft 6 a beveled gear 7 is keyed, and on the outer end of said shaft is a combined belt and drive wheel 8, having an eccentrically-positioned crank-handle thereon. The beveled gear 7 and the shaft 6 are steadied in their operation by a brace 10, which is attached to the said hanger and also to the upper portion of the superstructure, and on the 60 said gear is a crank-lug 11, having a crank-pin 12 extending therefrom. The hanger 5 is cut away on its inner lower side, as at 13, and below the said cut-away portion bearing-clips 14 are located, in which a stem 15 is 65 mounted and carries a beveled pinion 16, which meshes with the gear 7. The lower end of the stem 15 has a coupling-socket 17 thereon to receive the upper end of a rotatable dasher-rod 18 of a churn 19, the said dasher- 70 rod being continued downwardly into the churn and having secured thereto a dasher 20. The dasher-rod 18 is adapted to be attached or detached from the coupling-socket 17, and to accommodate these operations one side 75 of the said socket is left open, as at 21, Fig. 1, and a removable bolt 22 is employed to connect up the parts. The socket 17 is angular, and the upper end of the dasher-rod 18 is correspondingly formed, so as to obviate slipping and insure a proper rotation. The dasher 20 in the present instance consists of two curved bands 23, diametrically disposed and arranged vertically, and between the same alternately-arranged arms 24 project outwardly 80 from the dasher-rod and have enlarged free ends 25. Through the mechanism set forth 85 a churning operation can be successfully carried on by rotating the combined drive and band wheel 8.

Connected to the crank-pin 12 is a pitman 90 26, having its upper end movably secured to the free end of an operating-lever 27, which is fulcrumed at its opposite end on an upright 95 28, rising from the top of the superstructure. Connected to the lever 27 is the upper end of a washing-machine plunger 29, which extends downwardly through the top of a washing-machine 30, suitably situated thereunder, and carries a pounder 31, which 100 is perforated after the manner of ordinary devices of this character. Within the wash-

ing-machine 30 a perforated spring-cushioned follower 32 is located, as clearly shown in detail in Figs. 3 and 4. The said follower consists of an upper flat disk or head 33, having 5 connected to the under side thereof the upper portion of a coiled spring 34, whose lower end is attached to an inverted dished base-plate 35, and extending from the said base-plate upwardly through the spring and connected to the head 33 is a connecting-chain or analogous device 36, which is intended to hold the said head 33 at a predetermined distance from the base-plate and to normally assume a definite elevation in the washing-machine. In the operation of this machine the clothes are placed upon the head 33 of the follower, and successive reciprocations of the plunger 29 cause the pounder 31 to press the clothes downward against the said head 33 of 15 the follower, which yields to a downward pressure against the resistance of the spring 34, and the water is thrown up and the clothes thoroughly cleansed without injury or tearing action.

20 25 The churn and washing-machine are held on the base 1 in stationary position by fastening-bars 37 of a similar character, as clearly shown in Fig. 2, and the lever 27 has a series of openings 38 therein for the purpose of accommodating a change in position of the washing-machine or to attach other driving devices as may be found desirable and for the purpose of utilizing the power from the concentrated driving mechanism.

30 35 A crossed belt 39 runs from the combined drive and band wheel 8 to a grooved pulley 40 on the shaft 41 at an opposite point of the superstructure to drive a grindstone 42, keyed on said shaft. This grindstone 42 is located 40 near the end of the superstructure, so as to be easily accessible for grinding purposes.

45 From the foregoing it will be seen that a very convenient arrangement of mechanism is provided and particularly for the use of farmers. The labor of operating several devices is materially reduced and various kinds

of work can be accomplished at one and the same time by the exercise of power expended at a single point.

While the driving mechanism is shown arranged for manual operation, it will be understood that mechanical power may be substituted therefor, and also changes in the proportions, dimensions, and minor details of construction might be made and substituted for those shown and described without in the least departing from the spirit of the invention or sacrificing any of the advantages thereof.

Having thus described the invention, what is claimed as new is—

In a machine of the character set forth, the combination of a base having a frame rising therefrom, a drive-shaft on the upper part of the frame having an outer combined drive 65 and band wheel and an inner gear carrying a crank-pin, a depending hanger rotatably supporting a vertical spindle having an angular socket at the lower end thereof and also provided with a beveled pinion meshing with 70 said gear, a vertical shaft having an upper angular end removably fitted in the said socket and adapted to operate the dasher of a churn, another horizontal shaft on the frame, a belt running from said combined drive and band 75 wheel to said last-named shaft, an upright rising from one end of the frame, an operating-lever having one end fulcrumed in said upright and provided with a series of openings along the length of the same, a pitman 80 connecting the opposite end of the operating-lever with the crank-pin on the inner gear, and a plunger having its upper end adjustably connected to said operating-lever between the fulcrum of the latter and the pitman.

In testimony whereof I affix my signature in presence of two witnesses.

WILLIAM S. LANEY.
